UNITED STATES PATENT OFFICE.

JOHN W. HOLZ, OF DETROIT, MICHIGAN.

RADIATOR.

1,116,426.

Specification of Letters Patent. Patented Nov. 10, 1914.

Application filed March 29, 1912. Serial No. 637,056.

To all whom it may concern:

Be it known that I, JOHN W. HOLZ, a citizen of the United States of America, residing at Detroit, in the county of Wayne and State of Michigan, have invented certain new and useful Improvements in Radiators, of which the following is a specification, reference being had therein to the accompanying drawings.

10 In the construction of radiators for automobiles, condensers or the like it is desirable that the fluid therein be divided as much as possible to present the greatest area to the radiating or cooling surface and that 15 the parts be so disposed as to direct air from one to the other and thereby increase the efficiency of the operation.

This invention relates to a radiator and more particularly one adapted for use with 20 automobiles and to an arrangement thereof whereby the cooling liquid is so divided as to present a very large area per unit of volume in contact with the radiating surfaces and so that these radiating surfaces themselves 25 direct the air currents through the radiator in such manner as to thoroughly cool them.

The invention consists in the matters hereinafter set forth and more particularly 30 pointed out in the appended claims.

In the drawings, Figure 1 is a view in front elevation of a radiator that embodies features of the invention, and Fig. 2 is a view in transverse section through the radiator.

Referring to the drawings a hollow base 1 is held in separated spaced relation with a hollow header 2 by a plurality of upright tubes 3 which in turn are steadied by transversely disposed fin plates 4 or like members for steadyng the tubes horizontally and increasing the radiating surfaces thereof. Preferably the header and base are formed of sheet metal and their inner walls are 45 perforated to receive the tubes, the metal struck up from the perforations being out-turned as flanges to secure the tube ends. The tubes themselves are substantially triangular in section with their apices directed 50 toward the front of the radiator, and are disposed in staggered relation so that the wind currents passing between any tier of tubes are directed thereby against the tubes of the succeeding tier. With the acute portions of the tubes 3 disposed between the

pairs of tubes of the tiers in front, the currents of air are baffled and directed from wall to wall, thereby insuring automatic contact of the air with the tubes. By this construction a radiator is obtained that presents 55 a very large area of radiating surfaces per volume of inclosed fluid in the radiating pipes. The radiating effect is further enhanced by the disposition of the tubes which directs the air currents so that substantially all the air 60 that passes through the radiator comes in contact at one time or another with the tube walls. While herein shown as especially adapted for cooling liquid in a circulating system it is equally adapted for 65 use as a condenser and other purposes where it is desirable to present as large an area per unit of volume of the liquid as possible.

Obviously, changes in the details of construction may be made without departing from the spirit of the invention and I do not care to limit myself to any particular form or arrangement of parts.

What I claim as my invention is:

1. A radiator comprising a hollow base, a hollow header, tiers of upright tubes connecting the base and header, the tubes being substantially triangular in cross section with their apices directed toward the front of 85 the radiator and extended between the tubes of the tier in front of them, thereby avoiding straight and direct air passages through the radiator from the front thereof.

2. A radiator comprising a hollow base, a hollow header, tiers of upright tubes connecting the base and header, the tubes of one tier being staggered in relation to those of an adjacent tier, the tubes being substantially triangular in cross section with their 95 apices directed toward the front of the radiator and extended between the tubes in the tier in front of them, thereby avoiding straight and direct air passages through the radiator from the front thereof.

3. A radiator comprising a hollow base, a hollow header, tiers of upright tubes connecting the base and header, the tubes of one tier being staggered in relation to those of an adjacent tier, the tubes being substantially triangular in cross section with their apices directed toward the front of the radiator and extended between the tubes in the tier in front of them, thereby avoiding 105 straight and direct air passages through 110 the radiator from the front thereof.

the radiator from the front thereof and fin plates in spaced relation through which the tubes pass.

4. A radiator comprising a hollow base, 5 a hollow header, tiers of upright tubes connecting the base and header, the tubes being substantially triangular in cross section with their apices directed toward the front of the radiator and extended between 10 the tubes of the tiers in front of them and with the angle edges thereof in proximity

to the walls of adjacent tubes and intermediate the angle edges thereof, thereby avoiding straight and direct air passages through the radiator from the front thereof. 15

In testimony whereof I affix my signature in presence of two witnesses.

JOHN W. HOLZ.
